[57] CLAIM

The ornamental design for a clampable fishing rod
holder, substantially as shown and described.

DESCRIPTION

FIG. 1 is a perspective view of a clampable fishing rod
holder showing my new design;

FIG. 2 is a side elevational view of the clampable fish-
ing rod holder;

FIG. 3 is an elevational view looking from the right of
FIG. 2;

FIG. 4 is a top plan view of the clampable fishing rod
holder; and

FIG. 5 is a bottom plan view of the clampable fishing
rod holder.

FIG. 1.

FIG. 2.

FIG. 3.
